5 Claims. (Cl. 112—264)

This invention relates to a method and apparatus for forming buttonholes.

During the manufacture of articles of clothing such as shirts, blouses, etc., the buttonholes are formed by means of special sewing machines, which first form the embroidery of that portion of the article which will be one of the lips of the buttonhole, then form a stitch, termed a stopping stitch at one end of the lip, then form the embroidery of the second lip with a return movement of the fabric and finally form a second stopping stitch.

Normally opening of the buttonhole, that is to say cutting of the fabric between the two embroidered lips, is effected subsequently by means of a cutting device.

In the following description, the term "lip" will thus be used regardless of whether the buttonhole has already been cut or not.

When the fabric of the article is made from thermoplastic fibers, it is usual to cut the buttonhole with a hot cutting device so that the threads on the cut edges are welded, thus avoiding fraying of the lips of the buttonhole.

This hot cutting, when carried out after the formation of the buttonhole, constitutes a supplementary and delicate operation which is frequently the cause of defects.

It has already been proposed to carry out this hot cutting operation during the actual formation of the buttonhole on the machine, or in more precise manner, when forming the first lip of the buttonhole, the cutting device preceding the needle. However, this method of operation necessitates the provision on the machine of a number of supplementary members operating in the zone where the stitching is carried out. For example a pair of small rollers provided to keep the two lips of the buttonhole in position during the formation thereof. As a result of this the working zone is obstructed.

According to the present invention, there is provided a method of forming a buttonhole in an article of thermoplastic fabric using a sewing machine having a stitching needle, such method comprising embroidering the stitches for forming the first lip of the buttonhole by moving the fabric relative to the machine in a first direction, embroidering the stitching forming the second lip of the buttonhole by moving the fabric relative to the machine in a direction opposite to the first direction and hot cutting the fabric as the stitching of the second lip is effected the means for cutting being operated slightly in arrear of the stitching needle.

According to another aspect of the invention there is provided apparatus for forming buttonholes in thermoplastic fabric, such apparatus comprising a sewing machine having a needle and needle plate, means for translating fabric relative to said needle and plate first in one direction and then in the opposite direction, a cutting member movable between an out-of-the-way position below said plate and an operative position in which it projects above the plate to the side of the needle which is in arrear of the needle when the fabric is translated in said opposite direction, and means for heating the cutting member, the arrangement being such that, when fabric is caused to move in one direction, the cutting

2

member remains in its out-of-the-way position and, when the fabric is caused to move in the opposite direction, the heated cutting member is caused to move into cutting contact with the fabric. The means for translating the fabric may take any suitable form. For example they may take the form of feed means as illustrated in United States Patent No. 2,421,712 to Nichols issued June 3, 1947.

The cutting member is preferably fixed on a resilient support disposed on the needle plate and emerges through an opening formed in the latter. Heating thereof is advantageously controlled by the working cycle of the sewing machine so as to be set in operation with the start of the formation of the second lip of the buttonhole and to be stopped as soon as this operation is completed.

The method and apparatus according to the invention have the advantage of not complicating the working zone on the machine, since the cutting member is preferably located on the needle plate and it is no longer necessary to provide supplementary members maintaining the position of the two lips of the buttonhole during the formation thereof. In addition, this formation is carried out in a better manner, since it is made before the hot cutting of the fabric. Any danger of slipping of the fabric during the operation is thus avoided.

In order that the invention may more readily be understood the following description is given, merely by way of example, with reference to the accompanying drawings. In the drawings:

30 FIGURES 1 and 2 show diagrammatically a section of part of apparatus according to this invention, and illustrate respectively the position of the cutting member of such apparatus during the formation of the first lip and the second lip of the buttonhole and

35 FIGURE 3 is a diagram of the electric control circuit for the heating of the cutting member of the apparatus, the diagram also showing a number of the parts of the apparatus in detail and the relative positions of these parts in the apparatus.

40 In FIGURES 1 and 2 the heated cutting member indicated by the reference 1 is mounted on a resilient support 2, enclosed in the opening 3 formed in the lower face of the needle plate 4 of a sewing machine. The fabric T passes, as shown, between the needle plate and the usual presser foot 5.

45 Referring to FIGURE 1, during the formation of the first lip of the buttonhole, the cutting member, which is not heated, is urged into the opening 3 by the pressure of the fabric. During the formation of the first lip the fabric is moved by feed means such as those of aforementioned U.S. Patent No. 2,421,712, in a first direction as indicated by the arrow 17.

50 Referring to FIGURE 2, at the time of forming the second lip, the heated cutting member is urged by its resilient support against the fabric and causes the melting of fabric over the entire length of the buttonhole. During the forming of the second lip, the fabric is moved by the feed means in the opposite direction as indicated by the arrow 18. Thus the cutter 1, during this movement is in arrear of the needle hole 16 through which the needle of the sewing machine passes.

55 FIGURE 3 shows a buttonholing machine 6 of a type known per se and of which only the outline has been shown for greater simplicity. The main members controlling the heating of the cutting member are shown separately and in diagrammatic form to a larger scale. A 3-phase supply source is adapted to be connected to a supply circuit 8 of the machine via a main switch 9. Two of the phases supply the primary of a transformer 10 included in the heating circuit of the cutting member, which is connected to two conducting elements 7 and 7',

these being insulated from the needle plate and connected to the secondary of the transformer 10. Also included in the heating circuit are a switch 11 and two micro-switches 12 and 13.

The first micro-switch 12, which is connected to a lever 14 controlling the running of the machine, disconnects the heating circuit when the machine is stopped. Thus, in the event of the thread breaking or any accident, the operator can manually control the machine and repair the damage without the cutting member becoming operative. The second micro-switch 13 is connected to a cam 15 controlling the automatic production of the buttonhole.

In operation the switch 11 is closed manually and lever 14 actuated to close the micro-switch 12. As soon as the machine starts to cause the return movement of the fabric, the cam closes micro-switch 13, completing the circuit and thus heating the cutting member 1. As soon as the return movement of the fabric ceases the cam opens micro-switch 13 thus cutting off the heating.

We claim:

1. A method of forming a buttonhole in an article of thermoplastic fabric using a sewing machine having a stitching needle, such method comprising embroidering the stitches for forming the first lip of the buttonhole by moving the fabric relative to the machine in a first direction, embroidering the stitching forming the second lip of the buttonhole by moving the fabric relative to the machine in a direction opposite to the first direction and hot cutting the fabric as the stitching of the second lip is effected the means for cutting being operated slightly in arrear of the stitching needle.

2. A method of forming a buttonhole in an article of thermoplastic fabric using a sewing machine having a stitching needle, such method comprising embroidering the stitches for forming the first lip of the buttonhole by moving the fabric relative to the machine in a first direction, embroidering the stitching forming the second lip of the buttonhole by moving the fabric relative to the machine in a direction opposite to the first direction and hot cutting the fabric as the stitching of the second lip is effected said hot cutting being automatically controlled by said sewing machine to be operated slightly behind said stitching needle.

3. Apparatus for forming a buttonhole in thermoplastic fabric, such apparatus comprising a sewing machine having a needle and needle plate, means for translating fabric relative to said needle and plate first in one direction and

then in the opposite direction, a cutting member movable between an out-of-the-way position below said plate and an operative position in which it projects above the plate to the side of the needle which is in arrear of the needle when the fabric is translated in said opposite direction, and means for heating said cutting member, means for moving said cutting member into its operative position and control means operable on said heating means and coupled to said means for translating said fabric so as to actuate said heating means when said fabric is being translated in said opposite direction.

4. Apparatus as specified in claim 3 and including means defining an opening in said plate and resilient means disposed beneath said plate urging said cutting member through said opening.

5. Apparatus for forming buttonholes in thermoplastic fabric such apparatus comprising a sewing machine having a needle; a needle plate disposed beneath said needle; means defining an aperture in said needle plate; a cutting member disposed beneath said plate and on one side thereof a spring urging said cutting member through said aperture; electrical heating means for heating said cutting member; means for translating fabric over said plate from said needle in a direction towards said cutting member; further means for translating fabric in the direction opposite to said direction and control means effective to cause said heating means to heat said cutting member on operation of said further means.
